UNITED STATES PATENT OFFICE

WHEELER H. VIBBER, OF NEW LONDON, CONNECTICUT

CONDUIT CAP

Application filed May 11, 1928. Serial No. 277,068.

My invention relates to an improved conduit-cap for electric installations, the object being to provide a simple, convenient, sturdy conduit-cap constructed with particular reference to producing a fixture adapted to be applied to or removed from a conduit after the cables have been passed therethrough, without the necessity of severing or disconnecting such cables.

With these ends in view, my invention consists in a conduit-cap characterized by having a two-part separable mounting-plate, whereby the plate may be applied to or removed from a conduit through which the cables have already been passed without severing the same.

My invention further consists in a conduit-cap having a two-part separable mounting-plate, one part of which is formed with an installation-slot, whereby the plate may be applied to or removed from a conduit through which the cables have already been passed without severing the same.

My invention further consists in a conduit-cap characterized as described and having certain details of construction as will be hereinafter described and pointed out in the claims.

In the accompanying drawings:

Fig. 1 is a view in side elevation of one form which a conduit-cap, constructed in accordance with my invention, may assume, the cap being shown as applied to a conduit;

Fig. 2 is a similar rear view thereof;

Fig. 3 is an underside view thereof, with the conduit shown in section;

Fig. 4 is an enlarged-scale view of the cap in vertical longitudinal section on the line 4—4 of Fig. 2;

Fig. 5 is an enlarged-scale view in transverse section on the line 5—5 of Fig. 1;

Fig. 6 is a detail sectional view on the line 6—6 of Fig. 3;

Fig. 7 is a top view of the main mounting-plate member;

Fig. 8 is a detached front view of the same; Fig. 9 is a detached perspective view of the clamping-member of the separable two-part mounting-plate; and

Fig. 10 is a view corresponding to Fig. 3 but showing a modified form of my improved separable two-part mounting-plate.

In carrying out my invention as herein shown, the main mounting-plate member 15 is formed at its rear end with a centrally-located upstanding rounded mounting-lug 16 preferably formed with a transverse perforation 17 for the reception of the lag-screw 18 by means of which the cap as a unitary fixture and the conduit 19 are anchored to an adjacent wall 20 or other equivalent external support, such as a pole. The said mounting-lug corresponds in shape and size to a clearance-notch 21 formed in the lower edge of the rounded rear face or wall of the dome-like hood 22 of the fixture. When the hood is set over the plate, the edge of the said notch rests directly upon the edge of the lug forming a weather-joint, while an integral guard-flange 23, projecting beyond the inner face of the lug 16 overlaps the notch 21 from within the hood and substantially prevents the weather from entering the fixture by fitting against the inner face of the hood around the notch therein. A rounded ledge 24, formed on the inside of the lug at the base thereof and highest at its central portion deflects any water that may enter the conduit through the perforation 17 in the lug, upon either side of the inwardly-overhanging U-shaped lip 25 standing above the vertical socket 26 formed in the said main mounting-plate member 15 for the reception of the conduit 19 upon the upper edge of which the said lip rests.

Under the construction described, the hood may be readily applied to and removed from the mounting-plate without disturbing the same or the lag-screw 18, by means of which the fixture as a unit is anchored to some adjacent object, as already described.

To adapt my improved conduit-cap 15 to be applied to or removed from a conduit through which the cables have already been passed and from which they emerge, I form the said main mounting-plate member 15 with a clearance-slot 27 intersecting the socket 26 and normally closed by a tongue 28 projecting forwardly from the secondary or clamping member 29 of the two-part separable plate, the said member 29 being formed with a segmental inwardly-overhanging lip 30 substantially completing the circle of the lip 25. The said clamping-member 29 is provided at its ends with outstanding arms 31 perforated as at 32 for the passage of clamping-screws 33 which enter threaded bores 34 formed in oppositely-extending lugs 35 located at the opposite ends of an integral segmental clamping-collar 36 depending from the lower face of the mounting-plate and complementing the curve of the clamping-member 29, the said collar forming part of the socket 26 before mentioned. The curvature of the said collar 36 and of the central portion of the clamping-member 29 and the length of the clamping-screws 33 provide for a considerable range of variation in the diameter of the conduit 19 upon which the fixture may be mounted. The inner face of the said clamping-member 29 is provided with the usual serrations 37 for gripping the conduit. The main mounting-plate 15 and the clamping-member 29 thereof form, in effect, a separable two-part mounting-plate. At its forward end the main mounting-plate member 15 is provided with a large rectangular notch 38 centrally intersected by the installation-slot 28 aforesaid and flanked by parallel corresponding arms 39 which receive between them and support the two halves 40 and 41 of the porcelain insulator. The said halves of the insulator are formed upon their adjacent edges with semi-circular notches 42 which, when the parts are assembled, form circular passages for the cables. The edges of the said insulator halves are grooved as at 43 to adapt them to receive the adjacent edges of the rectangular notch 38 in the usual manner of such fixtures.

For securing the hood 23 in place, it is formed at opposite points in its side walls with bosses 44 mounting upwardly and inwardly inclined binding-screws 45 which engage inclined walls 46 at the upper ends of recesses 47 in the side walls of the mounting-plate member 15, as shown in Fig. 6.

In the modified construction shown by Fig. 10, the mounting-plate is made in two separable parts 48 and 49 each formed with integral clamping-flanges 50 and 51 respectively having extended ends for the reception of clamping-screws 52. The main member of the plate, that is, the part 48 thereof, is formed at its forward end with a large rectangular notch 53 corresponding to the notch 38 aforesaid for the reception of the two-part insula-

tor, while the secondary member or part 49 of the plate is provided with an upstanding mounting-lug 54 corresponding to the lug 16 of the construction first described.

My modified construction above described provides, as does my preferred construction already described, for the application to and removal of the fixture from a conduit without disconnecting or severing cables already installed therein and emerging therefrom.

I claim:

1. In a conduit-cap for electrical installations, the combination with a two-part separable mounting-plate comprising a main mounting-member having a conduit-receiving socket element and an installation-slot intersecting the same, and a secondary or clamping-member having a conduit-receiving socket element co-acting with the complementary feature of the said main member to grip the conduit and also having a forwardly-extending tongue fitting into the said slot to form a closure therefor, and a hood fitting over the said two-part separable mounting-plate to which it may be applied or removed after the installation thereof upon the conduit.

2. In a conduit-cap for electrical installations, the combination with a two-part separable mounting-plate comprising a main mounting-member having a conduit-receiving socket element, an insulator-receiving notch, and an installation-slot leading from the said notch into the said socket element, and a secondary or clamping-member normally closing the said installation-slot, and a hood fitting over the said two-part separable mounting-plate to which it may be applied or removed after the installation thereof upon the conduit.

3. In a conduit-cap fixture for electrical installations, the combination with a two-part separable mounting-plate, the two parts of which are respectively provided with complementary socket-elements together forming a separable socket for the reception of the end of a conduit and one of the said parts having an installation-slot; of a two-part separable insulating member carried by one part of the said two-part mounting-plate; and a hood covering the said two-part mounting-plate and the said two-part insulating member and formed independently thereof; whereby the fixture may be applied to or removed from a conduit after the wires have been installed therein.

4. In a conduit-cap fixture for electrical installations, the combination with a two-part separable mounting-plate, the two parts of which are respectively provided with complementary socket-elements together forming a separable socket for the reception of the end of a conduit and one of the said parts having an installation-slot and the other a complementary closure therefor; of a two-part separable insulating member carried by one part

of the said two-part mounting-plate; and a hood covering the said two-part mounting-plate and the said two-part insulating member and formed independently thereof; whereby the fixture may be applied to or removed from a conduit after the wires have been installed therein.

In testimony whereof, I have signed this specification.
